CLAIM

The ornamental design for a cutting board, as shown and described.

DESCRIPTION

FIG. 1 is an isometric view of a cutting board, embodying a new design;

FIG. 2 is a top plan view of the cutting board of FIG. 1; FIG. 3 is a rear side elevation view of the cutting board of FIG. 1;

FIG. 4 is a left side elevation view of the cutting board of FIG. 1;

FIG. 5 is a front side elevation view of the cutting board of FIG. 1;

FIG. 6 is a right side elevation view of the cutting board of FIG. 1; and,

FIG. 7 is a bottom plan view of the cutting board of FIG. 1. The broken lines shown in the drawings are for illustrative purposes only and form no part of the claimed design. The dash-dot lines are for illustrating boundaries of the claimed portions of the invention and form no part of the claimed design.
